US0D1072564S

(12) **United States Design Patent** (10) **Patent No.:** **US D1,072,564 S**
(45) **Date of Patent:** **** Apr. 29, 2025**

(54) **EXTRUDER DIE PLATE FOR FOOD
PROCESSING**

(71) Applicant: **AAK AB**, Malmo (SE)

(72) Inventor: **Jaclyn Steffey**, Louisville, KY (US)

(73) Assignee: **AAK AB**, Malmo (SE)

(**) Term: **15 Years**

(21) Appl. No.: **35/518,681**

(22) Filed: **Oct. 17, 2022**

(80) **Hague Agreement Data**

Int. Filing Date: **Oct. 17, 2022**

Int. Reg. No.: **DM/224463**

Int. Reg. Date: **Oct. 17, 2022**

Int. Reg. Pub. Date: **Oct. 20, 2023**
